(57) **CLAIM**

The ornamental design for an accessory simulative of an airplane, as shown and described.

DESCRIPTION

FIG. 1 is a side elevational view showing our new design for an accessory simulative of an airplane;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.
